Primary Examiner — Marissa J Cash*Assistant Examiner* — Rebecca Tsehay(74) *Attorney, Agent, or Firm* — Ladas & Parry LLP(57) **CLAIM**

The ornamental design for an electronic cigarette device, as shown and described.

DESCRIPTION

FIG. 1 is a front, right, and top perspective view of an electronic cigarette device showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right, and top perspective view of the electronic cigarette device in using state;

FIG. 10 is a rear, left, and bottom perspective view of the electronic cigarette device in using state; and,

FIG. 11 is an enlarged view of the circled portion 11 in FIG. 2.

The broken lines in the drawings depict portions of the electronic cigarette device that form no part of the claimed design.

1 Claim, 11 Drawing Sheets(56)
